POWER DRIVEN SHAMPOOING DEVICE

Alice M. Stuckey and Lewis Stuckey, Seattle, Wash., and Marcus J. Fassbinder, Wrangell, Territory of Alaska; said Lewis Stuckey and said Fassbinder assignors to said Alice M. Stuckey

Application October 8, 1938, Serial No. 233,984

5 Claims. (Cl. 15—22)

This invention relates to a shampooing device. More particularly, this invention relates to a power driven shampooing device in which the scalp contacting portions of the shampooing fingers move in and out in a manner simulating the movements of a person's fingers in shampooing.

Heretofore a number of massaging apparatuses have been devised for use in connection with facial massages and the like. These devices are 10 inapplicable for use in shampooing and massaging of the scalp and hair in view of the fact that the prior art devices either provide a rotary motion, which obviously would cause the hair to become 15 entangled in the rotating members, or such devices provide merely a vibrating action which is insufficient for proper shampooing and massaging of the scalp and hair, or failed to provide the desired individual in and out motion of the fingers.

20 In prior commercial practice the scalp and hair has been massaged and shampooed by the fingers of the operators and no mechanical devices have been available which provide the suitable individual in and out movement simulating the movement of one's fingers. Furthermore, due to the 25 manual effort necessary for hand massaging and shampooing, the scalp and hair commonly have not been properly massaged and shampooed. In view of the widely recognized beneficial results obtaining from thorough and proper massaging of 30 the scalp, the industry has long desired a device which was power driven and which would provide for a thorough shampooing and massaging action simulating the movement of one's fingers in 35 shampooing and massaging.

It is an object of this invention to provide a plurality of fingers and power driven means to impart the desired individual in and out movement to the scalp contacting portions of the 40 fingers to provide for proper massaging and shampooing of the hair and scalp. It is a further object of this invention to provide delivery and control means so that the liquids used in shampooing may be delivered through the shampooing 45 device, readily subject to control by the operator, and delivered onto the scalp and hair being massaged in close proximity to the shampooing fingers. It is a further object to provide separate control means for the soap and water used in 50 shampooing so that the desired amount of either will be readily available. It is a further object to utilize the liquids used in the shampooing operation as the lubricants for the finger driving mechanism.

55 It is a further object of the invention to provide

rubber shampooing fingers, metallic pins disposed therein, means to mount the pins for oscillating movement, and power driven means to oscillate individually the pins and in turn the shampooing fingers, i. e., to provide the desired individual in 5 and out movement of the scalp contacting portions thereof. It is a further object of the invention to provide a plurality of shampooing fingers disposed about a center and to provide means to move the scalp contacting portions of 10 the fingers substantially radially towards and away from said center.

It is a further object of the invention to provide a device which is simple, compact, economical as 15 to cost of manufacture and cost of operation, and capable of operating for relatively long periods of time without requiring mechanical attention.

The above mentioned general objects of our invention, together with others inherent in the 20 same, are attained by the device illustrated in the following drawings, the same being preferred exemplary forms of embodiment of our invention, throughout which drawings like reference numerals indicate like parts:

Figure 1 is a vertical sectional view with parts 25 shown in elevation of a device embodying this invention and with parts broken away and with the fingers shown in a full line position and a dotted line position for two of the fingers to illustrate the movement of the fingers; 30

Fig. 2 is a view partly in section and partly in plan taken substantially on broken line 2—2 of Figure 1;

Fig. 3 is a bottom plan view with parts broken 35 away taken substantially on broken line 3—3 of Figure 1, the fingers being shown perpendicular to the head of the device in Figure 3;

Fig. 4 is a detached plan view of the cam member employed in this invention;

Fig. 5 is a view partly in section and partly in 40 plan taken substantially on broken line 5—5 of Figure 1;

Fig. 6 is a detached fragmentary sectional view 45 taken substantially on broken line 6—6 of Figure 5;

Fig. 7 is a fragmentary sectional view showing a modified form of the pin member shown in Figure 1;

Fig. 8 is a view similar to Fig. 2 showing a modified form of the invention and particularly as respects the driving means and showing separate soap and water delivery means;

Fig. 9 is a view similar to Figure 1 showing a modified form of the invention and particularly 55

as respects the means for mounting the pins disposed within the finger members; and

5 Fig. 10 is a fragmentary sectional view of the form of the invention shown in Fig. 9, illustrating an alternative means for securing the rubber fingers to the pin members.

10 Referring to Figs. 1 and 2 of the drawings, an enclosed flexible cable 11, which is of common construction and is broken away, connects to a suitable source of power (not shown). A pinion 12 is mounted on the internal driving member of cable 11 and serves to transmit power therefrom to the bevel gear 13. The bevel gear 13 is connected to the cam 14 (see also Fig. 4) and may 15 be integral therewith as shown in Fig. 1. Cam 14 is provided with suitable trackways 15 and 16 for reception therein of the portions 17 of the pins 18. The pins 18 are embedded in a rubber supporting means 19 which may be integral with the 20 rubber fingers 20. The pins 18 are provided with pivotal mounting members 21 which are embedded in the rubber supporting means 19. Plates 22 and 23 are mounted on the opposite 25 faces of the rubber supporting means 19 and are spaced apart by means of an annular ring 24. Hollow pins 25 connect between the plates 22 and 23. One means of securing the pins 25 to the plates is by expanding the ends of the pins as 30 shown in Fig. 6. The openings 26 (see also Fig. 3) of the hollow pins 25 serve as passageways for delivery of fluid in the chamber 27 onto the scalp being massaged. As a means of securing the device together, the plate 22 abuts the shoulder 28 in the housing 29 and the annular ring 30 35 is threadedly connected with the housing 29 and serves to retain the plates 22 and 23 in proper place.

40 The flexible conduit 31 (see Fig. 2) is broken away and connects to a source (not shown) of liquid soap under pressure. The liquid soap in the flexible conduit 31 is urged into the passageway 32. A valve member, comprising spring 33, valve means 34 and plunger 35, serves to control the flow of liquid soap from the opening 32 into 45 the passageway 36. Liquid soap which is permitted to enter passageway 36 moves into the chamber 27 and thence out openings 26 onto the scalp being massaged.

50 The flexible conduit 37 is broken away and connects to a source (not shown) of water under pressure. The water in flexible conduit 37 enters the passageway 38. The valve mechanism, comprising the spring 39, valve means 40 and plunger 41, serves to control the passage of water from the 55 passageway 38 to the passageway 42'. Water entering the passageway 42' is delivered into the chamber 27 and thence out openings 26 onto the scalp being massaged. The liquid soap and water in the chamber 27 surround the bevel gear 13 60 and pinion 12 and serve as lubricants for said bevel gear and pinion, as well as lubricants between the portions 17 of the pins 18 and the trackways 15 and 16 of the cam 14.

65 In the operation of the device shown in Figs. 1 to 6 inclusive, a source of liquid soap under pressure and water are connected to the flexible conduits 31 and 37, respectively. The motor driving the flexible cable 11 is started. The speed of drive of the flexible cable 11 may vary greatly 70 within the scope of this invention. In a practical embodiment of this invention, we have found it satisfactory to drive the flexible cable 11 at a speed of about 250 r. p. m. The rotary motion on the internal driven member within the flexible 75 cable 11 is imparted to the pinion 12. The gear

ratio between the pinion 12 and the bevel gear 13 may also vary greatly. In said practical embodiment of this invention with the pinion 12 rotating at the rate of 250 r. p. m., we provided a gear ratio of substantially four to one between 5 the pinion 12 and the bevel gears 13, i. e., substantially four revolutions of the pinion to one revolution of the bevel gear. This provides for movement of the fingers 20 in and out at a speed 10 providing the desired massaging and shampooing action. Preferably the speed of the fingers is sufficiently slow to permit the fingers to positively move in and out. In view of the fact that the rubber fingers contact the scalp and the rubber fingers have positive give therein, too great a speed 15 will lessen the effectiveness of the device and little movement will be imparted to the fingers. Rotary movement of the bevel gear 13 provides similar rotary movement to the cam 14 which is secured to the bevel gear. The portions 17 of the 20 pins 18, which fit within the grooves 15 and 16 of the cam 14 are preferably rounded as indicated in Figure 1, so as to follow the grooves 15 and 16 with less friction. As the cam 14 rotates, the portions 17 of the pins 18 move individually in a 25 radial direction on pivot members 21. Preferably the plate 22 is cut away to provide openings 42 which are somewhat larger than the radial movement of the pins 18 at this point. This will reduce the compression of the rubber 19 at this 30 point and facilitates the oscillating movements of the pins 18 in radial direction. Also preferably the rubber 19 is cut away at 43 to likewise facilitate the oscillating movements of the pins 18. As the pins 18 oscillate, their lower end portions supporting the rubber fingers 20 cause the rubber fingers 20 to move individually in and out in a 35 radial direction. As the rubber fingers 20 move in and out in a radial direction, the operator may depress plunger 35 to introduce soap into the 40 chamber 27 and depress the plunger 41 to introduce water therein. The water and the soap serve to lubricate pinion 12, bevel gear 13 and the portions 17 of the pins 18 in the trackways 15 and 16 of the cam 14. The pinion 12 and bevel gear 45 13 also serve to thoroughly intermix the soap and water so that the liquids are delivered onto the scalp adjacent the fingers 20 in the desired condition for the shampooing and massaging treatment of the hair and scalp.

50 In Fig. 7 of the drawings, we have shown an alternative construction where a finger 20 is provided with a pin 44 which may be substituted in place of the pins 18 in Figs. 1 to 6 inclusive. The rubber supporting means 45 may be substituted 55 for the rubber supporting means 19 of the earlier figures. The member 46, on the pin 44, serves as a pivot means in place of the pivot mounting member 21 of the previous figures. Also preferably the opening 47 is used for the same purposes 60 as the opening 43 shown in Fig. 1. In place of the rounded portion 17 shown in connection with pin 18 there may be used the ball member 48 which is rotatively mounted on the pin 44. Such rotatively mounted ball members 48 will follow 65 the trackways 15 and 16 of the cam 14 with reduced friction.

70 We have provided a further alternative construction for the pivotal support of the pins in Figs. 9 and 10. In this modified form of the invention the parts similar to the parts shown in Fig. 1 of the drawings are provided with the same numbers or are broken away, and in the interest of brevity will not be repeated. The pins 49 have 75 rubber fingers 50 thereon. In this form of the

invention the three centrally disposed fingers 20, see Fig. 3, are eliminated and the fingers are all disposed in substantially a circle about a given center. Preferably a rubber sealing member 51 is 5 formed integral with the fingers 50 to prevent the escape of liquids around the fingers. Pins 49 are provided with ball members 52 to serve as the pivotal supports. Two plate members 53 and 54 are provided with mating cup shaped openings 10 to serve as bearings for the ball members 52. In this form of the invention the ball members 52 are the pivotal supports and oscillate in metallic bearings provided in plates 53 and 54. In Fig. 10 the same pivotal support is provided as shown in 15 Fig. 9. Here the rubber sealing member 51 is eliminated and the rubber fingers 55 are molded with cutaway portions to interfit with flanges 56 preferably formed integral with the pins 57.

In Fig. 8 of the drawings we have provided a 20 modified form of the invention where the soap and water are each delivered separately and are not premixed prior to application on the scalp and hair. The passageway 36 connects by a conduit 58 with the centrally disposed opening 62. 25 Thus by operation of the plunger 35 the soap may be delivered directly onto the scalp and water may be delivered by operation of the plunger 41 as previously described.

As an alternative method of driving the cam 14 30 shown in Figs. 1 to 6, inclusive, and thence the fingers, the shaft 59 in Fig. 8 is connected by a flexible cable (not shown) to a source of power. Worm 60 intermeshes with gear 61 which is in turn connected with cam 14 by any suitable means. 35 In the foregoing description of this invention, we have illustrated the flexible cable to connect the shampooing device to a suitable source of power. By this well known means the weight of the motor is not carried by the shampooing device. 40 However, if desired, instead of the usual flexible cable connection for transmitting the power, the motor may be directly mounted on shampooing device and connected to provide the proper rotary motion of the cam. Also we have shown a plurality of manners of pivotally mounting the fingers 45 so that the fingers will individually move radially in an in and out manner to properly simulate the in and out movement of the fingers of a person in massaging or shampooing.

50 Obviously, changes may be made in the forms, dimensions and arrangement of the parts of our invention, without departing from the principle thereof, the above setting forth only preferred forms of embodiment.

55 We claim:

1. In a shampooing device, a plurality of finger members mounted about a central axis; a plurality of pin members each having one end portion disposed within a finger member; pivot means carried by and disposed intermediate the length of the pin members; a rubber supporting means mounting said pivot means, whereby each pin member 60 may oscillate with said pivot and rubber supporting means serving as the pivotal support; and means to individually oscillate the other end portions of the pin members in a radial direction as respects the said central axis.

2. In a shampooing device, a plurality of finger members mounted about a central axis; a plurality of pin members each having one end portion disposed within a finger member; pivot means carried by and disposed intermediate the length of the pin members; a disc like rubber supporting member mounting said pivot means, said rubber supporting member being cut away on the surface adjacent the other end portions of pin members, whereby said rubber supporting member will serve 10 to position the pivot means and permit relatively free movement of the end portions of the pin members so that each pin member may oscillate with said pivot means and said rubber supporting member serving as the pivotal support; and means 15 to individually oscillate the other end portions of the pin members in a radial direction as respects the central axis.

3. In a shampooing device, a plurality of finger members mounted about a central axis; a plurality of pin members each having one end portion disposed within a finger member; pivotal supporting means disposed intermediate the length of said pin members; means to individually oscillate the other end portions of the pin members in a radial direction as respects the said central axis; a plurality of liquid channels disposed with openings in close proximity to said finger members; and means connecting a source of liquid under pressure to said liquid channels.

4. In a shampooing device, a plurality of finger members mounted about a central axis; a plurality of pin members each having one end portion disposed within a finger member; pivotal supporting means disposed intermediate the length of said pin members; chamber forming means providing a chamber enclosing the other end portions of said pin members; driven oscillating means disposed in said chamber and serving to individually oscillate the other end portions of the pin members in a radial direction as respects the said central axis; means to supply said chamber with water and liquid soap, whereby said driven oscillating means will intermix said soap and water and said soap and water will serve to lubricate said oscillating means; and channel means delivering said liquid from said chamber through openings in close proximity to said fingers.

5. In a shampooing device, a plurality of finger members mounted about a central axis; a plurality of pin members each having one end portion disposed within a finger member; pivot means carried by and disposed intermediate the length of the pin members; a rubber supporting means mounting said pivot means, whereby each pin member may oscillate with said pivot and rubber supporting means serving as the pivotal support; means to individually oscillate the other end portions of the pin members in a radial direction as respects the said central axis; a plurality of liquid channels disposed with openings in close proximity to said finger members; and means connecting a source of liquid under pressure to said liquid channels.
